TRIMMING MECHANISM FOR BLIND STITCH
SEWING MACHINESHorace F. Gruman, St. Louis, Mo., assignor to
Geoffrey Stevenson, Buffalo, N. Y.Original application April 12, 1937, Serial No.
136,466. Divided and this application October
25, 1937, Serial No. 170,916

25 Claims. (Cl. 112—123)

This invention relates to new and useful improvements in sewing machines generally, although more particularly to a trimming mechanism employed in a machine of the blind stitch type adapted especially for hemming operations.

The application constitutes a division of my parent application for Sewing machines, Serial No. 136,466, filed April 12, 1937.

The principal object of my invention is to provide a trimming mechanism between the hemmer and the needle for trimming the inner edge of the hem immediately prior to the hem being anchored by the blind stitch forming mechanism.

With the above and other objects in view which will more fully appear, the nature of the invention will be more clearly understood by following the description, the appended claims, and the several views illustrated in the accompanying drawings.

In the drawings:

Figure 1 is a front elevation of a sewing machine constructed in accordance with my invention.

Figure 2 is a partial top plan view thereof.

Figure 3 is an enlarged plan view of the presser foot, showing the ridge forming element, the trimming mechanism, and the stitch forming elements.

Figure 4 is a perspective view of the needle driving mechanism.

Figure 5 is an enlarged front elevation of the movable trimmer.

Figure 6 is an end elevation thereof.

Figure 7 is a rear view of the movable trimmer.

Figure 8 is a detail plan view of the front end of the presser foot, and

Figure 9 is a side elevation thereof.

The sewing machine which embodies my invention includes a main frame A comprising a standard 5 having upper and lower arms 6, 7 extending laterally from the left side thereof, the free end of the upper arm being provided with a transverse and upwardly opening recess 8 forming a resultant horizontal arm extension 9 and a vertical end wall 10, the left hand end of the arm extension being formed centrally with a vertical recess 11 forming resultant front and rear bearing lugs 12, 13.

A main shaft 14 extends longitudinally along the upper arm 6 and across the standard 5 and is suitably journaled therein, the left hand end of the shaft extending across the recess 11 above the arm extension 9 and being journaled in the end wall 10, the arm extension 9 and the end wall

10 thus cooperating to form an extended bearing for the shaft.

A horizontal presser foot B having an opening 15 is located below the arm extension and is rigidly secured thereto by spaced vertical arms 16, 17. A ridge forming element C is mounted in the lower frame arm 7 for projecting a ridge of hemmed fabric upwardly through the presser foot opening 15 into needle penetrating position.

A horizontal needle shaft 18 is journaled in the spaced bearing lugs 12, 13 and is therefore located below and at right angles to the main shaft 14, and directly above the opening 15 of the presser foot B. Attached to the forward end of the needle shaft and projecting towards the left thereof, is a needle arm 19 and attached to said arm is a curved needle 20. A rock arm 21 which is fixed to the needle shaft intermediate the bearing lugs 12, 13 is driven from the main shaft by an eccentric 22 fixed thereon in the recess 8 and a cooperating pitman 23 which extends upwardly through the recess 11. Thus, the needle will be reciprocated horizontally over the presser foot opening 15 once for each rotation of the main shaft, the forward or penetrating stroke of the needle being from left to right.

A loop taker 24 and a loop spreader 24^a cooperate with the needle to form a line of overedge blind stitches. The loop taker reciprocates across the ridge forming means, and the loop spreader reciprocates in a path disposed generally to the right of the ridge forming means. These elements, in themselves, form no part of the present invention, except insofar as they cooperate in the general combination claimed hereinafter, and since their general functions are well known in the art and their specific constructions and drive connections are shown and described in detail in my parent application for U. S. Letters Patent Serial No. 136,466, filed April 12, 1937, further detailed disclosure herein is thought to be unnecessary. It is deemed sufficient to state that each time the needle 20 begins its backward stroke, the loop spreader 24^a will pick up the needle thread loop and carry it forwardly into position to be entered by the loop taker 24 and the loop taker will then continue its forward stroke and position its looper thread loop to be entered by the needle during its next forward stroke.

It is desirable to trim the inner edge of the hem prior to the hem being stitched to the body fabric and to provide means for turning the hem in advance of the trimming operation. To this end, the presser foot B is provided in front of

the needle path, with an L-shaped opening comprising a longitudinal opening 25 and a communicating lateral opening. The lateral opening is formed by a forwardly extending foot portion 26 and a rearwardly extending foot portion 27. The under face of the portion 26 inclines downwardly and rearwardly, and the upper face of the portion 27 inclines downwardly and rearwardly, said upper and lower faces conjointly forming a resultant rearwardly and downwardly inclined slot 28 for receiving the nose 29 of a folder 30 which is secured to a bracket arm 31 removably mounted on the front wall of the lower frame arm 7, the folder extending around the rearwardly projecting portion 27. The longitudinal opening 25 is located in front of and in register with the opening 15, and the lateral opening is located on the right hand side of the opening 25. A horizontal ledger blade 32 is seated in a transverse groove 33 formed in the upper face of the foot on the left of the opening 25 and in rear of the nose 29 of the folder, and is adjustably clamped therein by a screw 34, the cutting edge of the blade preferably projecting slightly into the opening 25 and lying in parallelism with said opening. A horizontal movable blade or knife 35 cooperates with the ledger blade 32 to trim the upturned edge of the hem, the movable blade being reciprocable across the rear end of the opening 25, and being provided with a toe or extension 36 which is maintained in yieldable sliding contact with said ledger blade. The cutting edge of the movable blade inclines rearwardly towards the cutting edge of the ledger blade to provide a shearing cutting action between the blades, and the toe 36 is located at the rear end of the cutting edge of the movable blade. The movable blade is removably attached to a holder 37 by a longitudinally extending clamp 38 and screw 39, the holder and the clamp being conjointly formed with a dovetailed groove for receiving the blade. The heel of the holder 37 is pivotally connected by a transverse pin 40 to the lower arm 41 of a supporting lever 42 which is fulcrumed on a horizontal stud or bearing 43 fixed to and extending forwardly from a bracket 44 attached to the upper frame arm 6. The upper arm 44 of the lever is pivotally connected by a link 45 to an eccentric pin 46 fixed to the front end of the needle shaft 18. The holder 37 is provided with a rigid and upstanding lever arm 47 which is located intermediate the cutting edge of the movable blade and the pivot 40, and a coil spring 48 is interposed between the arm 47 and the lower arm 41 of the supporting lever 42 and functions to maintain the movable blade in yieldable contact with the ledger blade. The left hand end of the clamp 38 terminates in a guide 49 for the trimmed off strip, the guide being curved downwardly and rearwardly and terminates in close fitting relation to the toe 36. Cooperating with the under face of the presser foot B to feed the fabric rearwardly from the trimming mechanism toward and past the needle path is a suitable lower feeding mechanism. This mechanism includes a main 4-motion feed dog 113 and a 4-motion differential feed dog 114. The main feed dog 113 includes two long side sections 115, 116 and a short intermediate section 117 which operate in the rear portions of the feed slots of the work clamp. The side sections are disposed on opposite sides of the presser foot opening 15 and extend forwardly to a point slightly in front of the needle path, but the intermediate section is disposed wholly in rear of

the needle path and in rear of said opening. The differential feed dog includes two long side sections and a short intermediate section which operate in the front portions of the feed slots in the work clamp. The side sections are disposed on opposite sides of the presser foot opening 15 and extend forwardly to a point slightly in front of said opening, but the intermediate section 120 cooperates with the foot immediately in front of the opening 15 and its rear end terminates in front of the trimmer ledger blade 32. The side sections 115, 118 and 116, 119 of the feed dogs are arranged in overlapping relation for engaging the body fabric throughout the combined length of both dogs.

A back and forth movement is imparted to the differential feed dog 114 during each rotation of the main shaft and its feed stroke can be varied. Similarly, a back and forth movement will be imparted to the main feed dog during each rotation of the main shaft, and its feed stroke also can be varied. Since the feeding mechanisms, in themselves, form no part of the present invention, except insofar as they cooperate in the general combination claimed hereinafter, and since these mechanisms are disclosed in detail in my parent case Serial No. 136,466, filed April 12, 1937, and covered in another divisional application for U. S. Letters Patent Serial No. 170,918, filed October 25, 1937, further detailed description herein is thought to be unnecessary.

It will be seen that the edge portion of the hem fold immediately after leaving the hemmer, is directed upwardly by the opening 25 and is then trimmed by the cooperating horizontal cutting elements 32, 35. The trimmed edge portion of the hem fold is then turned down against the body fabric by engaging the bridge on the presser foot between the aligned openings 25 and 15 whereby the entire trimmed hem fold will be positioned flat against the body fabric immediately prior to the same being engaged by the ridge forming element C. Immediately thereafter the hem fold will be joined to the body fabric by the line of blind stitches in which the needle thread loops first enter the body fabric and pass upwardly through the hem fold and are concatenated by a covering thread which is formed into loops overlying the trimmed edge of the hem fold. This produces an extremely flat and covered hem fold.

From the foregoing it will be observed that both the needle and the movable trimmer blade are operated from the needle shaft; that the needle moves from left to right during its forward or penetrating stroke; that the movable blade moves from right to left during its cutting stroke; that the trimming elements are located between the needle and the folder, and that the ridge forming element projects the trimmed hem upwardly into needle penetrating position.

It is of course to be understood that the details of structure and arrangement of parts may be variously changed and modified without departing from the spirit and scope of my invention.

I claim:

1. In a blind stitch sewing machine, means for joining the edge of a superposed fabric layer to a base fabric layer comprising a horizontal presser foot having an opening, a stitch forming mechanism operating entirely above the foot and including a needle mounted for reciprocations across the opening, means for projecting a ridge of said layers upwardly through the opening into needle penetrating position, and a trimming mechanism located in front of the opening

trimming the edge of the superposed layer prior to said layers being ridged.

2. In a blind stitch sewing machine, means for joining the edge of a superposed fabric layer to a base fabric layer comprising a horizontal presser foot having an opening, a stitch forming mechanism operating entirely above the foot and including a needle mounted for reciprocations across the opening, means for reciprocating the needle, means for projecting a ridge of said layers upwardly through the opening into needle penetrating position, a trimming mechanism located in front of the opening for trimming the edge of the superposed layer prior to said layers being ridged, and driving connections between the needle reciprocating means and the trimming mechanism for operating the latter.

3. In a blind stitch sewing machine, means for joining the edge of a superposed fabric layer to a base fabric layer comprising a horizontal presser foot having an opening, a stitch forming mechanism operating entirely above the foot and including a needle mounted for reciprocations across the opening, means for reciprocating the needle, means for projecting a ridge of said layers upwardly through the opening into needle penetrating position, a trimming mechanism located in front of the opening for trimming the edge of the superposed layer prior to said layers being ridged, said trimming mechanism including a horizontal ledger blade fixed to the foot and a cooperating horizontally reciprocatory movable blade, and driving connections between the needle reciprocating means and the movable trimmer blade for operating the latter.

4. In a blind stitch sewing machine, means for joining the edge of a superposed fabric layer to a base fabric layer comprising a horizontal presser foot having an opening, a stitch forming mechanism operating entirely above the foot and including a needle mounted for reciprocations across the opening, means for projecting a ridge of said layers upwardly through the opening into needle penetrating position, and a trimming mechanism located in front of the opening for trimming the edge of the superposed layer prior to said layers being ridged, said trimming mechanism including a horizontal ledger blade fixed to the foot and a cooperating horizontally reciprocatory movable blade.

5. In a blind stitch sewing machine, means for joining the edge of a superposed fabric layer to a base fabric layer comprising a frame having a laterally extending arm, a horizontal presser foot secured to said arm and provided with an opening, a stitch forming mechanism operating entirely above the foot and including a rock shaft and a needle carried thereby for reciprocations across said opening, means for projecting a ridge of said layers upwardly through the opening into needle penetrating position, and a trimming mechanism located in front of the opening for trimming the edge of the superposed layer prior to said layers being ridged, said trimming mechanism including a ledger blade and a movable blade, and driving connections between the needle rock shaft and the movable blade.

6. In a blind stitch sewing machine, means for joining the edge of a superposed fabric layer to a base fabric layer comprising a frame having a laterally extending arm, a horizontal presser foot secured to said arm and provided with an opening, a stitch forming mechanism operating entirely above the foot and including a rock shaft and a needle carried thereby for reciprocations

across said opening, means for projecting a ridge of said layers upwardly through the opening into needle penetrating position, and a trimming mechanism located in front of the opening for trimming the edge of the superposed layer prior to said layers being ridged, said trimming mechanism including a horizontal ledger blade fixed to the foot and a cooperating horizontally reciprocatory movable blade, and driving connections between the needle rock shaft and the movable blade.

7. In a blind stitch sewing machine, means for joining the edge of a superposed fabric layer to a base fabric layer comprising a frame having a laterally extending arm, a horizontal presser foot secured to said arm and provided with an opening, a stitch forming mechanism operating entirely above the foot and including a rock shaft and a needle carried thereby for reciprocations across said opening, means for projecting a ridge of said layers upwardly through the opening into needle penetrating position, and a trimming mechanism located in front of the opening for trimming the edge of the superposed layer prior to said layers being ridged, said trimming mechanism including a vertical lever fulcrumed intermediate its ends on the frame arm, a horizontal ledger blade fixed to the foot, a cooperating horizontally reciprocatory movable blade connected to the lower arm of said lever, and driving connections between the needle rock shaft and the upper arm of said lever.

8. In a blind stitch sewing machine, means for joining the edge of a superposed fabric layer to a base fabric layer comprising a frame having a laterally extending arm, a horizontal presser foot secured to said arm and provided with an opening, a stitch forming mechanism operating entirely above the foot and including a rock shaft and a needle carried thereby for reciprocations across said opening, means for projecting a ridge of said layers upwardly through the opening into needle penetrating position, and a trimming mechanism located in front of the opening for trimming the edge of the superposed layer prior to said layers being ridged, said trimming mechanism including a vertical lever fulcrumed intermediate its ends on the frame arm, a horizontal ledger blade fixed to the foot, a cooperating horizontally reciprocatory movable blade, a holder for the movable blade pivotally connected to the lower arm of said lever, spring means between the holder and the lever for maintaining the movable blade in yieldable contact with the ledger blade, and driving connections between the needle rock shaft and the upper arm of said lever.

9. In a blind stitch sewing machine, means for joining the edge of a superposed fabric layer to a base fabric layer comprising a horizontal presser foot having an opening, a stitch forming mechanism operating entirely above the foot and including a needle mounted for reciprocations across the opening, means for projecting a ridge of said layers upwardly through the opening into needle penetrating position, a trimming mechanism located in front of the opening for trimming the edge of the superposed layer prior to said layers being ridged, said trimming mechanism including a horizontal ledger blade fixed to the foot and a cooperating horizontally reciprocatory movable blade, and means for reciprocating the needle and the movable blade whereby the penetrating stroke of the needle and the trimming stroke of the blade will be imparted simultaneously.

10. In a blind stitch sewing machine, means for joining a hem fold to a body fabric comprising a horizontal presser foot having an opening, a stitch forming mechanism operating entirely above the foot and including a needle mounted for reciprocations across the opening, means for projecting a ridge of body fabric and hem upwardly through the opening into needle penetrating position, a hemmer located in front of the opening, and a trimming mechanism located intermediate the hemmer and the opening for trimming the inner edge of the hem prior to the body fabric and hem being ridged.
11. In a blind stitch sewing machine, means for joining a hem fold to a body fabric comprising a horizontal presser foot having an opening, a stitch forming mechanism operating entirely above the foot and including a needle mounted for reciprocations across the opening, means for projecting a ridge of body fabric and hem upwardly through the opening into needle penetrating position, said foot being provided with a longitudinal guide slot located in front of and in alignment with the opening therein, a hemmer having its nose positioned to direct the hem into said guide slot, and a trimming mechanism operating across the rear end of the slot for trimming the inner edge of the hem prior to the body fabric and hem being ridged.
12. In a blind stitch sewing machine, means for joining a hem fold to a body fabric comprising a horizontal presser foot having an opening, a stitch forming mechanism operating entirely above the foot and including a needle mounted for reciprocations across the opening, means for projecting a ridge of body fabric and hem upwardly through the opening into needle penetrating position, said foot being provided with a longitudinal guide slot located in front of and in alignment with the opening therein, a hemmer having its nose positioned to direct the hem into said guide slot, and a trimming mechanism operating across the rear end of the slot for trimming the inner edge of the hem prior to the body fabric and hem being ridged, said trimming mechanism including a horizontal ledger blade fixed to the foot at one side of the slot, and a cooperating reciprocatory blade movable horizontally across said slot.
13. In a sewing machine for joining a hem fold to a body fabric, the combination with a horizontal presser foot having an opening, of a stitch forming mechanism operating entirely above the foot and including a needle mounted for reciprocations across the opening, means for projecting a ridge of body fabric and hem upwardly through the opening into needle penetrating position, a trimming mechanism located in front of the opening for trimming the inner edge of the hem prior to the body fabric and hem being ridged, and a lower feeding mechanism including a feed dog cooperating with the bottom of the foot for feeding the fabric from the trimming mechanism to the needle path.
14. In a sewing machine for joining a hem fold to a body fabric, the combination with a horizontal presser foot having an opening, of a stitch forming mechanism operating entirely above the foot and including a needle mounted for reciprocations across the opening, means for projecting a ridge of body fabric and hem upwardly through the opening into needle penetrating position, a trimming mechanism located in front of the opening for trimming the inner edge of the hem prior to the body fabric and hem being ridged, and a lower feeding mechanism for feeding the fabric rearwardly from the trimming mechanism to a point in rear of the needle, said feeding mechanism including a main feed dog and a differential feed dog, the latter feeding the fabric rearwardly from the trimming mechanism towards the needle path.
15. In a sewing machine for joining a hem fold to a body fabric, the combination with a horizontal presser foot having an opening, of a stitch forming mechanism operating entirely above the foot and including a needle mounted for reciprocations across the opening, means for projecting a ridge of body fabric and hem upwardly through the opening into needle penetrating position, a hemmer located in front of the opening, a trimming mechanism located intermediate the hemmer and the opening for trimming the inner edge of the hem prior to the body fabric and hem being ridged, and a lower feeding mechanism including a feed dog cooperating with the bottom of the foot for feeding the fabric rearwardly from the hemmer past the trimming mechanism.
16. In a sewing machine for joining a hem fold to a body fabric, the combination with a horizontal presser foot having an opening, of a stitch forming mechanism operating entirely above the foot and including a needle mounted for reciprocations across the opening, means for projecting a ridge of body fabric and hem upwardly through the opening into needle penetrating position, a hemmer located in front of the opening, a trimming mechanism located intermediate the hemmer and the opening for trimming the inner edge of the hem prior to the body fabric and hem being ridged, and a lower feeding mechanism for feeding the fabric rearwardly including a main feed dog and a differential feed dog, the latter feeding the fabric from the hemmer and past the trimming mechanism.
17. In a blind stitch sewing machine for joining a hem fold to a body fabric, the combination with a horizontal presser foot, of an overedge stitch forming mechanism operating entirely above the foot and including a needle mounted for substantially horizontal reciprocations above the foot, means for projecting a ridge of body fabric and a trimmed hem fold into needle penetrating position, a horizontal trimming means located in front of the needle, means for directing the edge portion of the hem fold in a vertical plane to the trimming means, and means located between the trimming means and the needle for turning the trimmed edge portion down against the body fabric prior to the formation of said fabric ridge.
18. In a blind stitch sewing machine for joining a hem fold to a body fabric, the combination with a horizontal presser foot, of an overedge stitch forming mechanism operating entirely above the foot and including a needle mounted for substantially horizontal reciprocations above the foot, a loop taker and a loop spreader cooperating with each other and with the needle, means for projecting a ridge of body fabric and a trimmed hem fold into needle penetrating position, the penetrating stroke of the needle being from left to right, said loop spreader reciprocating on the ridge of the ridge forming means and said loop taker reciprocating across the ridge forming means, a horizontal trimming means located in front of the needle, means for directing the edge portion of the hem fold in a vertical plane to the trimming means, and means

- located between the trimming means and the needle for turning the trimmed edge portion down against the body fabric prior to the formation of said fabric ridge.
5. 19. In a blind stitch sewing machine for joining a hem fold to a body fabric, the combination with a horizontal presser foot, of an overedge stitch forming mechanism operating entirely above the foot and including a needle mounted 10 for substantially horizontal reciprocations above the foot, means for projecting a ridge of body fabric and a trimmed hem fold into needle penetrating position, a hemmer located in front of the ridge projecting means, a horizontal trimming means located between the ridge projecting means and the hemmer, means located in front of the trimming means for directing the edge portion of the hem fold as it leaves the hemmer in a vertical plane to said trimming 15 means, and means located between the trimming means and the needle for turning the trimmed edge portion down against the body fabric prior to the formation of said fabric ridge.
20. In a blind stitch sewing machine for joining a hem fold to a body fabric, the combination with a horizontal presser foot having front and rear openings and a bridge therebetween, of a stitch forming mechanism operating entirely above the foot and including a needle mounted 25 for reciprocations across the rear opening, a ridge forming element for projecting a ridge of body fabric and hem upwardly through said rear opening into needle penetrating position, a horizontal trimming mechanism for the hem fold 30 operating in front of the ridge forming means including a stationary ledger blade located at one side of the front opening and a cooperating movable blade reciprocal across said front opening, and means for directing the edge portion of 35 the hem fold in a vertical plane to the trimming means, said bridge effecting the turning down of the trimmed hem fold against the body fabric prior to the ridge therein being formed.
21. In a blind stitch sewing machine for joining a hem fold to a body fabric, the combination with a horizontal presser foot having front and rear openings and a bridge therebetween, of a stitch forming mechanism operating entirely above the foot and including a needle mounted 40 for reciprocations across the rear opening, a ridge forming element for projecting a ridge of body fabric and hem upwardly through said rear opening into needle penetrating position, a hemmer located in front of the ridge forming element, a 45 horizontal trimming mechanism for the hem fold located between the ridge forming element and the hemmer and including a stationary ledger blade located at one side of the front opening and a cooperating movable blade reciprocal across 50 said front opening, and means for directing the edge portion of the hem fold in a vertical plane to the trimming means, said bridge effecting the turning down of the trimmed hem fold against the body fabric prior to the ridge therein being 55 formed.
22. In a blind stitch sewing machine, means for joining the edge of a superposed fabric layer to a base fabric layer and covering said edge comprising a horizontal presser foot having an opening, a stitch forming mechanism operating entirely above the foot and including a needle mounted for reciprocations across the opening, a loop taker and a loop spreader cooperating with each other and with the needle to form concatenated joining and overedge stitches, 60 means for projecting a ridge of said layers upwardly through the opening into needle penetrating position, and a trimming mechanism located in front of the opening for trimming the edge of the superposed layer prior to said layers 65 being ridged.
23. In a blind stitch sewing machine, means for joining the edge of a superposed fabric layer to a base fabric layer comprising a horizontal presser foot having an opening, a stitch forming mechanism operating entirely above the foot and including a needle mounted for reciprocations across the opening, means for projecting a ridge of said layers upwardly through the opening into needle penetrating position, a trimming mechanism located in front of the opening for trimming the edge of the superposed layer prior to said 70 layers being ridged, and a lower feeding mechanism including a feed dog cooperating with the bottom of the foot for feeding the fabric from 75 the trimming mechanism to the needle path.
24. In a blind stitch sewing machine, means for joining a hem fold to a body fabric comprising a horizontal presser foot having an opening, a stitch forming mechanism operating entirely above the foot and including a needle mounted for reciprocations across the opening, means for projecting a ridge of body fabric and hem upwardly through the opening into needle 80 penetrating position, a hemmer located in front of the opening, and a trimming mechanism located intermediate the hemmer and the ridge projecting means for trimming the edge of the hem fold prior to the body fabric and the hem being ridged.
25. In a blind stitch sewing machine, means for joining a hem fold to a body fabric comprising a horizontal presser foot having an opening, a stitch forming mechanism operating entirely above the foot and including a needle mounted for reciprocations across the opening, means for projecting a ridge of body fabric and hem upwardly through the opening into needle 85 penetrating position, a hemmer located in front of the opening, a trimming mechanism located intermediate the hemmer and the ridge projecting means for trimming the edge of the hem fold prior to the body fabric and the hem being ridged, and a lower feeding mechanism for feeding the fabric rearwardly including a main feed 90 dog and a differential feed dog, the latter feeding the fabric from the hemmer and past the trimming mechanism.

HORACE F. GRUMAN.
